UNITED STATES PATENT OFFICE

167,445

DOUBLE WASHING MACHINE

John M. Cook, Jr., Dallas, Tex.

Application November 8, 1949, Serial No. 5,937

Term of patent 14 years

(Cl. D49—1)

To all whom it may concern:

Be it known that I, John M. Cook, Jr., residing at Dallas, in the county of Dallas, State of Texas, have invented a new, original, and ornamental Design for a Double Washing Machine, of which the following is a specification, reference being had to the accompanying drawing, forming part thereof.

In the drawing:

Fig. 1 is a front perspective view of a double washing machine, showing my new design;
Fig. 2 is a rear perspective view thereof.
Fig. 3 is a top plan view, and
Fig. 4 is an end elevational view thereof.

I claim:

The ornamental design for a double washing machine, substantially as shown.

JOHN M. COOK, JR.
